No. 36,457.

Patented July 21, 1903.

UNITED STATES PATENT OFFICE.

FRED L. DAGGETT, OF SOMERVILLE, MASSACHUSETTS.

DESIGN FOR A BOX-COVERING.

SPECIFICATION forming part of Design No. 36,457, dated July 21, 1903.

Application filed May 16, 1903. Serial No. 157,489. Term of patent 7 years.

To all whom it may concern:

Be it known that I, FRED L. DAGGETT, a citizen of the United States, residing at Somerville, county of Middlesex, and State of Massachusetts, have invented a new, original, and ornamental Design for a Box-Covering, of which the following is a description, reference being had to the accompanying drawing, forming a part hereof.

10 The drawing shows a plan view of the box-covering.

Having described my invention, what I claim as new, and desire to secure by Letters Patent of the United States, is—

The ornamental design for a box-covering, 15 as shown.

FRED L. DAGGETT.
